UNITED STATES PATENT OFFICE.

RAYMOND A. MULL, OF BENTON HARBOR, MICHIGAN, ASSIGNOR TO THE COOLAMP COMPANY, OF BENTON HARBOR, MICHIGAN, A CORPORATION OF MICHIGAN.

ACETYLENE LAMP.

Application filed March 15, 1922. Serial No. 543,883.

To all whom it may concern:

Be it known that I, RAYMOND A. MULL, a citizen of the United States, and a resident of Benton Harbor, Berrien County, Michigan, have invented a certain new and useful Improvement in Acetylene Lamps, of which the following is a specification.

This invention relates to acetylene lamps of that kind in which a water chamber is provided with means for gradually feeding the water therefrom to the chamber containing the carbide, whereby the acetylene gas is generated in the usual and well known manner, and is then fed to a burner tip of any suitable character. More specifically considered, the invention relates to that particular kind of lamp in which the construction is such that the device may be conveniently carried on the belt, or on the cap or in the hand of a miner, or by any other person desiring a strong and powerful light of this character.

Generally stated, therefore, the object of the invention is to provide a novel and improved construction whereby an acetylene lamp is provided which will be reliable in its operation, convenient to open and close, when it is desired to replenish the water or the carbide, and which may be conveniently carried without discomfort from the heat generated while the lamp is in operation.

It is also an object to provide certain details and features of construction and combinations tending to increase the general efficiency and the desirability of an acetylene lamp of this particular construction.

To this and other useful ends the invention consists in matters hereinafter set forth and claimed and shown in the accompanying drawings in which—

Figure 1 is a vertical section of an acetylene lamp embodying the principles of the invention, showing the water valve closed.

Figure 2 is a horizontal section on line 2-2 in Figure 1.

Figure 3 is a rear elevation of said lamp.

Figure 4 is a detail sectional view of the means for feeding water from the upper chamber to the lower chamber, showing the water valve open.

Figure 5 is an enlarged section on line 5-5 in Figure 4.

As thus illustrated, the invention comprises an upper water chamber 1 and a lower carbide chamber 2 screw connected together

at 3, whereby they can be separated to refill the carbide chamber. The upper water chamber has a cap 4 to permit filling thereof. A tube 5 extends downwardly from the water chamber to the carbide chamber, and is gradually tapered downward internally thereof. An adjustable controller 6 extends downwardly in said tube, being tapered at 7 to correspond with the internal taper of the tube. The upper end of said controller 6 has a handle 8 for the rotation thereof, and has a screw connection 9 with the top of the water chamber, whereby rotation of this controller will move it up and down to control the feed of the water downward to the carbide. A collar 10 is slidable up and down on the tube 5 and is connected by a rigid arm 11 with the lower end of the member 6, whereby rotation of this member causes it to move up and down and thereby move the collar 10 up and down to clean the outer surface of said tube. The acetylene gas generated in the carbide chamber passes upward through the filter 12 to the tube 13 which leads to the burner tip 14 disposed on the side of the water chamber and provided with a reflector 15 of any suitable character to throw the light in the desired direction. A back plate 16, of non-heat conducting material, is hinged at 17 at its upper end to the back of the water chamber 1, and is provided with curved springs 18 which form a yielding yoke to receive the carbide chamber, and to grip the latter, thereby holding the plate 16 in upright position. A hook 19, or any suitable means, is attached to the back of the plate 16 by which to carry the lamp, either in the hand or on the belt or cap of the user. In this way, and by the shield formed by the plate 16, the user is protected against discomfort from the heat generated by the lamp. It will be seen that the lower portion of the plate 16, as shown in Figure 3, is much wider than its upper end as the heat is generated in the carbide chamber which is held by the springs 18 in the manner shown. When it is desired to replenish the carbide, the plate 16 is swung back into the position shown in dotted lines in Figure 1, thereby releasing the carbide chamber, and permitting the latter to be unscrewed from the bottom of the water chamber, in a manner that will be readily understood. The control of the feeding means for feeding the

water downward from the water chamber to the carbide chamber is effectively accomplished by the rotation of the member 6, the space between the tapered portion 7 and the interior of the tube 5 being uniformly varied by the up and down movement of said member, so that the water will feed more rapidly or more slowly, depending upon requirements.

10 It will be seen that the tapered valve 7 is very much greater in length than its maximum diameter, so that it has one very gradual or slight taper downward. The internal taper of the tube 5 is at the same 15 angle as the taper of the member 7, so that the opposing surfaces of the valve member and its valve seat are always parallel, as shown in Figures 1 and 4, up or down endwise adjustment of said member varying 20 the distance between the two opposing tapered surfaces. At the same time, however, the distance at one point between the two surfaces is always the same as the distance at other points between the two surfaces, 25 for any particular adjustment of the valve mechanism thus provided. The tube 5 is tapered internally for its full length, and when the valve is closed the entire interior of the tube is in engagement with the tapered exterior of the valve 7.

30 It will be seen therefore, that the devices 10 and 11 form a stop to limit the upward movement of the valve member 6, and prevents withdrawal of this member or removal thereof from the lamp.

35 What I claim as my invention is—

1. In an acetylene lamp the combination 40 of a water chamber, a carbide chamber, a feed tube extending downward from the water chamber and into the carbide chamber, carried by the bottom wall of the water chamber, in position to permit water to enter the upper end of the tube which bottom wall forms a removable cap for the top of 45 the carbide chamber, a downwardly tapered valve member extending through said tube, means forming a screw adjustment for causing endwise movement of said member, comprising screw threads on the upper portion 50 of said member, said member extending a distance below said tube, a stop on the lower end of said member to limit the upward movement thereof, said tube being tapered for its full length internally thereof 55 at the same angle as said member, forming a valve seat for said member, whereby end-

wise adjustment of said member will vary the distance between the surface of said member and the surface of said tube, with one surface parallel with the other.

60 2. A structure as specified in claim 1, said member extending below the lower end of said tube.

65 3. A structure as specified in claim 1, in combination with means carried by the lower end of said member and movable up and down therewith to clean the outer cylindrical surface of said tube.

70 4. In an acetylene lamp, the combination of a water chamber, a carbide chamber, a feed tube extending downward from the water chamber to the carbide chamber, and endwise adjustable and downwardly tapered valve member in said tube, and means mounted on said member and movable up and down therewith on said tube when the valve is operated thereby to clean the outer cylindrical surface of said tube, serving to limit the upward movement of said member.

75 5. A structure as specified in claim 4, said member having a rotary screw adjustment therefore to cause said endwise movement thereof, and said cleaning means comprising a collar slidable up and down on said tube by the adjustment of said member.

80 6. In an acetylene lamp, the combination of an upper water chamber, a lower carbide chamber, a separable connection between the two chambers, means for feeding water downward from the upper chamber to the lower chamber, a shield to protect the wearer against the heat generated by the lamp, forming a back plate therefor, means to hinge the upper end of said shield to the water chamber, means to detachably connect the lower portion of said shield to the carbide chamber, whereby the shield will be rigid with the lamp body, but so that the shield may be detached from the carbide chamber to permit one chamber to be disconnected from the other, and means on the back of said shield to carry the lamp.

85 7. A structure as specified in claim 6, said means for detachably connecting the shield to the carbide chamber comprising springs 90 for embracing said chamber, forming a yielding yoke to receive and grip the chamber.

95 8. A structure as specified in claim 7, said shield being a flat plate of non-heat conducting material.

100 RAYMOND A. MULL.
